UNITED STATES PATENT OFFICE.

RICHARD TRETHAWAY, OF PARSONS, AND CHARLES TRETHAWAY, OF WILKESBARRE, PENNSYLVANIA.

DESIGN FOR A CAN-CLOSURE.

SPECIFICATION forming part of Design No. 34,500, dated May 14, 1901.

Application filed April 4, 1901. Serial No. 54,401. Term of patent 7 years.

To all whom it may concern:

Be it known that we, RICHARD TRETHAWAY, residing at Parsons, and CHARLES TRETHAWAY, residing at Wilkesbarre, in the county of Luzerne and State of Pennsylvania, citizens of the United States, have invented and produced a new and original Design for a Can-Closure, of which the following is a specification.

This invention relates to a new and original design for a can-closure; and the essential features reside in the design as illustrated in the accompanying facsimile drawings, wherein—

Figure 1 is a side elevation of a can-closure embodying the design. Fig. 2 is a transverse vertical section of the same.

The design is characterized by a lower body of general cylindrical contour and comprising

ing a lower flange 1 and circumferential corrugations 2 above said flange. A cap 3 is circumferentially offset from the upper portion of the said body and comprises a vertical face or entablature 4, with outstanding elliptical projections 5, and on the cap is a top 6, of curved arcurate form, as shown.

Having thus described the invention, what is claimed as new is—

The design for a can-closure, as herein shown and described.

In testimony that we claim the foregoing as our own we have hereto affixed our signatures in the presence of two witnesses.

RICHARD TRETHAWAY.
CHARLES TRETHAWAY.
